TOWER YARDER ASSEMBLY

Gerald Frink, Seattle, Wash., assignor to Washington Iron Works, Seattle, Wash., a corporation of Washington

Application November 3, 1947, Serial No. 784,919

11 Claims. (Cl. 212—144)

1

This invention relates to a tower yarder assembly, one more especially which is portable in nature, and it is one object of the invention to provide a tower yarder in which the tower, the spooling drums, and the engine of the yarder are carried upon a mobile stand.

It is a further and important object to provide, as the tower for the yarder, a spar member mounted upon the stand for vertical swinging movement from an approximately horizontal carrying position into an upright operating position, and with the assembly so constructed and arranged as to permit the engine of the yarder, when the spar is being erected, to be employed both for hoisting the spar and for stabilizing the latter against lateral sway.

As a further object still, the invention aims to provide a tower yarder assembly in which the erected spar is stepped upon a thrust bearing and in which this bearing is independent of the pivot mounting which swingably supports the spar.

The invention has the still further and important object of providing a yarder assembly embodying a swingably mounted spar and which is characterized in that the pivot axis lies close to the ground level.

A still further and important object resides in so engineering the spar and its pivot mounting as to assure, when the spar occupies its lowered horizontal position, ample clearance for a tractor to run under the spar and hook onto the yarder for towing the latter from one to another site.

The foregoing, together with other features of the invention and the advantages attained thereby, will appear and be understood in the course of the following description and claims, the invention consisting in the novel construction and in the adaptation and combination of parts hereinafter described and claimed.

In the accompanying drawings:

Figure 1 is a view in side elevation illustrating a tower yarder assembly constructed in accordance with the now-preferred embodiment of the present invention, full and dotted lines being employed to represent the spar in elevated and lowered positions.

Fig. 2 is a fragmentary view to an enlarged scale principally in front elevation but partially in section, and with the spar being here shown as occupying its lowered position. In both this and the preceding view, and for simplicity in illustration, the crawler treads which give mobility to the vehicular body upon which the yarder is

2

carried are shown only in outline with no attempt at detail.

Fig. 3 is a fragmentary view to an enlarged scale and shown partly in elevation and partly in section to detail the head end of the spar member.

Fig. 4 is a horizontal section on line 4—4 of Fig. 3; and

Fig. 5 is a fragmentary vertical section to a yet larger scale and taken on a line radial to the spar assembly for detailing one of the several swivel-sheave units which accommodate the main guy lines for the assembly.

The numeral 10 designates a vehicular body mounted upon front and rear non-powered crawler units 11 and 12, respectively, and having at each end of the body a draw-bar, as 13 and 14, arranged to be tow-coupled to a tractor (not shown). The body provides a platform reaching forwardly somewhat beyond the bearing center of the front crawler unit, and swivel-mounted by a king-bolt 15 in centered position upon this forward reach is a chair 16. There are provided by this chair, and placed at diametrically opposite sides of the swivel center, upstanding spaced pairs of apertured lugs 17, and removably received through the apertures of these lugs is a horizontal pivot pin 20. There is also carried upon the frontal end of the platform, but removed rearwardly from the chair and preferably such as to occupy a position proximate to but lying slightly behind the transverse vertical center of the front, crawler units 11, a relatively heavy thrust plate 21 formed to present a facing socket of semi-spherical form. In a manner which will be hereinafter described, the spar member of the present invention, and which I denote generally by 23, is arranged when occupying its erected position to be stepped in this socket, the footing element comprising a mating ball-shaped butt 24 made an integral part of the spar.

At the rear end and upon opposite sides of the yarder there are provided standards 25 between which is journaled a sheave 26, and placed below such sheave at or about the floor line of the platform is a second sheave 27. The two sheaves act in complement to guide a spar-hoisting line 28, this line having one of its ends made fast to the yarder, passing therefrom about a sheave 30 carried upon an out-jutting framework 31 of the spar 23, thence having a complete turn around the two sheaves 26 and 30 and, after again passing over the sheave 26, running downwardly to the sheave 27 and thence forwardly to a spooling drum, this spooling drum being one

of a severality of drums denoted 29 and which, together with a yarder engine 32, are carried upon the platform. The driving connections including control brakes and clutches between the engine and the several spooling drums are or may be conventional and require no illustration.

Now reverting to the spar member, the foot-ing end therof, in addition to the rearwardly jutting framework 31, is also provided with a forwardly jutting outrigger frame 33. This frame 33 is composed of two matching trestle-like structures having the limbs of the trestles joined at the ends by gussets 34 and tied, one gusset to the other, by a spreader bar 35.

The gussets 34 are apertured, and the location and spacing is such that, by slight lowering movement of the spar from the erected full-line position in which the same is shown in Fig. 1, the gussets will lodge in the interstices between the paired lugs of the swivel-mounted chair 16 and, bringing the apertures of the gussets into registration with the apertures of the lugs, permit the pivot pin 20 to be passed therethrough for coupling the one to the other, a continuation of the lowering movement then causing the spar to swing about the pin 20 as an axis with a coincidental lifting of the butt 24 out of its socket. When completely lowered, the spar occupies the position in which it is shown by dotted lines in Fig. 1, the spar then lying more or less horizontal to the ground. When moving the yarder, accomplished by coupling the draw-bar 13 to a tractor, such spar desirably has its front end supported upon the trailer bed of a lead truck travelling ahead of the tractor. It may be here pointed out that the outrigger frame 33 effectively elevates the hinged end of the lowered spar to enable the tractor to work freely under the latter.

The spar is hollow and, sectionally considered, is of a generally rectangular configuration framed from corner angle irons 36 faced with steel plates, and there is welded or otherwise secured upon the head end of the spar a collar 37 formed in its perimeter with a circumscribing groove 38. A ring 40 is revolvably fitted in this groove, and provided at diametrically opposite sides of this ring are spaced apertured ears 41 for the attachment, as by pins 42 and 43, of a main lead block 44 at one side and tail guys 45 at the other side of the ring. The main line which runs through this block and thence downwardly to a related one of the spooling drums is shown in Fig. 1 and designated 46.

Welded or otherwise rigidly secured to the spar to lie in surmounting relation to the collar is a cage structure composed, as shown, of horizontal plates 47 and 48 separated by web spacers 49, and at equidistantly spaced intervals about the circumference there is received between the top and bottom plates of this cage a severality of vertical pins, eight being shown. Four of these pins, denoted 50, are solid and serve as bearings for swivel eyes 51 arranged and adapted to engage auxiliary guy lines (not shown), and the other four pins, denoted 52 and alternating with the solid pins, are hollow and are made an integral part of swivel-yokes 53 supporting respective sheaves 54 which, with outlying blocks 55, each serve as a differential take-up for associated main guy lines 56. The draw-line 57 for this take-up tackle has one end anchored to the block 55 and, after making a complete turn about the sheave 54 and the block, is returned over the sheave and thence through the hollow pin 52 (see Fig. 5) into the spar, running downwardly

through the latter and at the base of the spar being passed under a sheave 58 and thence to a related one of the spooling drums of the yarder.

In addition to the main line 45 and the several guy lines, namely tail, main and auxiliary, provision must be made for the haul-back line and also for the straw line, denoted by 60 and 61, respectively. At the very top of the spar I provide a swivel-mounted fair-lead 62 and a sheave 63, the haul-back line being arranged to pass through the fair-lead and over the sheave and, as with the lines 46 and 57, thence running downwardly to a related one of the spooling drums. The straw-line, which likewise is spooled about a related one of the drums, works through a block 64 supported at or about the mid-height of the spar.

Assuming that the spar occupies the lowered position in which it is shown by dotted lines in Fig. 1, the procedure in raising the spar is to first take up on the hoist line 28, causing the spar to swing upwardly about the pivot-pin 20 as an axis. Coincident with this elevational movement, the several main guy lines, which have been previously secured by their outer ends to suitably located anchoring stumps, are taken up or let out as may, in the respective instance, be necessary to stabilize the head-end of the spar. As the rising spar approaches its fully erected position, the swinging butt 24 will become seated in the socket of the step-bearing 21 and the hoisting drum is then momentarily set in this position while the pivot-pin 20 is withdrawn, following which the hoisting action is continued with the weight of the spar being now entirely borne by the step-bearing. The main guys are all drawn into taut conditions, their spooling drums locked, and the operation is then completed by running the outer ends of the auxiliary and tail guys around suitable anchoring stumps, this latter operation being accomplished in the customary manner, and which is to say by taking successive wraps about the stumps, drawing these wraps tight through power derived from the yarder engine, and spiking each wrap in turn.

A particular advantage of the invention and which should, perhaps, be stressed is that the semi-spherical socket with its mating butt 24 makes it possible to give to the spar a firm footing support even though the spar, when erected, occupies a position like or similar to that shown in Fig. 1, and which is to say in a position inclined from the perpendicular. Another advantage which should be expressly pointed out is that the two-point pivotal suspension by which the lowered spar is sustained upon a swivel-mounted chair, in conjunction with hoist and guy lines which lead from the spar to the spooling drums of the yarder and are at all times available for lifting the head end of the spar, make it possible when the yarder is being moved from one to another site to manipulate the yarder and its spar around bends which would be otherwise difficult if not impossible to negotiate. With the described arrangement, and assuming that the turning arc of an encountered bend is too short to accommodate the reach of the spar when the latter occupies its lowered horizontal position, the procedure is simply one of starting up the engine of the yarder and raising the spar in the degree necessary to shorten the horizontal span to the turning limit prescribed by the bend, coincidentally stabilizing this elevational movement by staking out main guy lines at each side of the roadway, and then gradually taking in or playing

out these guy lines on the related spooling drums as the yarder is manipulated around the bend. Upon completing the turn, the spar is again lowered to have its head end rest upon the lead truck.

It is thought that the invention will have been clearly understood from the foregoing detailed description of the preferred embodiment of the invention. Changes in construction may perforce be resorted to without departing from the spirit of the invention and it is my intention that the hereto annexed claims be read with a scope commensurate with the broadest interpretation which the employed language permits.

What I claim is:

1. In a tower mobile yarder assembly, a yarder carrying spooling drums together with a source of power for driving the drums, a straight spar swingably supported at its lower end by the yarder for movement from a lowered approximately horizontal position into an erected approximately vertical position and upon its head end carrying a plurality of sheaves each of which is swivel-mounted for self-alinement with guy lines passing over the respective sheaves, a hoisting line connected to the spar and powered from one of the spooling drums for elevating the spar, and a plurality of guy lines working through the sheaves, arranged to be secured by one end of each to anchoring stumps, and having their other ends operatively attached to others of the said spooling drums for stabilizing the head end of the spar during the act of raising the latter.

2. In a tower mobile yarder assembly, a yarder carrying spooling drums and an engine for driving the drums, a straight spar supported by the yarder for vertical swinging movement from a lowered approximately horizontal position into an erected upright position, the swing axis of said yarder occupying a plane which approximately coincides horizontally with the plane occupied by the drums and the engine, a hoisting line connected to the spar and powered from one of the spooling drums for raising the spar, a plurality of sheaves carried upon the head end of the spar each of which is swivel-mounted for self-alinement with guy lines passing over the respective sheaves, and guy lines arranged to be secured by one end of each to respective anchoring stumps and running therefrom to the sheaves and thence to others of the said spooling drums for stabilizing the head end of the spar during the act of raising the latter.

3. In a tower yarder assembly, a yarder carrying spooling drums together with an engine for driving the drums and presenting a step bearing occupying a plane which approximately coincides with the plane occupied by the drums and the engine, a spar supported by the yarder for vertical swinging movement from a lowered inactive position whereat the same occupies an approximately horizontal position into an operating upright position, the spar when occupying its said upright position footing upon the step bearing, and a hoisting line connected to the spar and powered from one of the spooling drums for elevating the spar.

4. In a tower yarder assembly, a yarder carrying spooling drums and an engine for driving the drums, a spar supported by the yarder for vertical swinging movement from a lowered inactive position whereat the same occupies an approximately horizontal position into an operating upright position, a step-bearing upon the yarder offset longitudinally from the swing axis of the spar

to the side of the latter opposite from the lowered head of the spar, a hoisting line connected to the spar and powered from one of the spooling drums for elevating the spar, and a foot provided upon the spar and arranged by upward swinging movement of the spar to register with and seat upon the step-bearing and thereby transfer from the swing axis to the step-bearing the vertical thrust of the upright spar.

5. In a tower yarder assembly, a yarder, a spar provided at its base end with an out-jutting framework, a detachable hinge connection between the yarder and the free extremity of said out-jutting framework and acting to support the

10 spar for vertical swinging movement from a lowered approximately horizontal position into an upright position, a step-bearing upon the yarder off-set longitudinally from the swing axis of the spar to the side opposite that occupied by the lowered head of the spar, a foot provided upon the spar and arranged by upward swinging movement of the spar to register with and seat upon the step-bearing, and means for raising and lowering said spar.

15 6. In a portable spar assembly, a mobile base, a spar provided adjacent its bottom end with outrigger structures jutting fore and aft from diametrically opposite sides, a hinge connection between the base and the free extremity of one of

20 said outrigger structures supporting the spar for vertical swinging movement from a lowered approximately horizontal position into an upright position, a power-driven hoist means connecting with the free extremity of the other outrigger

25 structure for raising the spar, a step-bearing upon the yarder off-set longitudinally from the swing axis of the spar to the side opposite that occupied by the lowered head of the spar, and a foot provided upon the spar and arranged by upward swinging movement of the spar to register with and seat upon the step-bearing.

30 7. In a tower yarder assembly, a mobile yarder carrying spooling drums together with an engine for driving the drums, a chair upon the front end of the yarder mounted for swivel movement about a vertical axis, a spar provided at its bottom end with a forwardly jutting outrigger structure, a hinge connection between the chair and the free extremity of said outrigger structure supporting

35 the spar for vertical swinging movement from a lowered approximately horizontal position into an upright position, a hoisting line connected to the spar and powered from one of the spooling drums for elevating the spar, a step-bearing upon the

40 yarder off-set longitudinally from the swing axis of the spar to the side opposite that occupied by the lowered head of the spar, and a foot provided upon the spar and arranged by upward swinging movement of the spar to register and seat upon the step-bearing.

45 8. In a tower yarder assembly, a yarder carrying spooling drums and an engine for driving the drums, a spar supported by the yarder for vertical swinging movement from a lowered approximately horizontal position into an upright position and presenting upon its head end a rigidly circumferentially grooved collar, a ring received

50 for rotary shifting movements in the groove of said collar and providing means for the attachment thereto of stabilizing tail guys, a block suspended from the ring and arranged to handle a main line spooled by one of its ends about one of the drums, and means also provided upon the head end of the spar for the attachment of main

55 guys and for handling a haul-back line which, as

with the main line, is spooled by one of its ends about one of the drums.

9. In a tower yarder assembly, a yarder carrying spooling drums and an engine for driving the drums, a spar supported by the yarder for vertical swinging movement from a lowered approximately horizontal position into an upright position and presenting upon its head end a rigid circumferentially grooved collar, a ring received for rotary shifting movements in the groove of said collar and providing means at one side thereof for the attachment thereto of stabilizing tail guys, a block suspended from the ring to lie diametrically opposite from said guy attachment and arranged to handle a main line spooled by one of its ends about one of the drums, a rigid cage surrounding the collar, a plurality of sheaves supported by the cage to lie at spaced intervals about the circumference of the latter and each acting to handle a main guy line spooled by one of its ends 20 about a related one of the drums, and means also carried by the spar and placed in surmounting relation to the cage and acting to handle a haul-back line which, like the main and guy lines, is spooled by one of its ends about one of the 25 drums.

10. A tower yarder assembly according to claim 9 in which the spar is of hollow construction and wherein the sheaves for the main guys are swivel-mounted with the swivel pins being hollow and opening by their bottom ends into the interior of the spar, access being provided to enable the inner ends of the guy lines to pass from the respective sheave into the bore of the related pin whence the line passes downwardly through the spar to 35 the spooling drum.

11. In a tower yarder assembly, a yarder carrying spooling drums and an engine for driving the

drums, a hollow upright spar supported by the yarder, and a plurality of sheaves swivel-mounted upon the head end of the spar and each acting to handle a main guy line spooled by one of its 5 ends about a related one of the drums, the swivel mountings comprising hollow pins each journaled to turn about a respective axis generally parallel to the longitudinal center line of the spar and having openings in the side and in the bottom of each said pin with said bottom opening being exposed to the interior of the spar, the side openings enabling the inner ends of the guy lines to pass from the respective sheave into the bore of the related pin and thence through the bottom opening downwardly through the spar to the spooling drum.
